ELEVATOR CONTROL SYSTEM

Austin E. Fribance, Rochester, and Thomas F. Jarvis, Warsaw, N. Y., assignors to Watson Elevator Company, Inc., a corporation of New York

Application October 28, 1949, Serial No. 124,208

20 Claims. (Cl. 318—158)

1

This invention relates to electrical elevator and hoist control systems of the variable voltage type.

One of the objects of the invention is to provide an electrical control system for the purposes aforesaid which provides improved control features and which is reliable and inexpensive to construct and adjust and maintain in operation.

Another object is to provide an electrical control system which may be embodied in standard units adapted to control elevator and hoist mechanisms of various types and capacities by using standard stock control units which may be readily adjusted when installed to suit the particular installation.

A further object is to provide an improved control system which will control the elevator mechanism so as to provide stepless acceleration and deceleration, thereby increasing the riding comfort and reducing shock loads on the mechanism.

It is also an object to provide a more efficient vertical transportation system.

In the drawing, the single figure is a straight-line schematic diagram of an elevator control system embodying the invention.

The invention is described in connection with a simple elevator system, but it is to be understood that it may be used in hoist systems and in other more complicated elevator systems or in other mechanisms employing similar drives for other purposes.

Referring now to the drawing, we have illustrated an elevator car 2 as suspended by a cable 4 which passes over a hoisting drum 5 to a counterweight 6. The hoisting drum 5 is fixed upon a shaft 7 operated by a hoisting motor M having an armature 8. The motor M is provided with a shunt field winding 9 connected across a pair of supply conductors 10 and 11 which may be supplied with direct current from a suitable source. A spring-operated brake 12 controlled by an electromagnetic coil 13 is provided for preventing operation of the hoisting drum 5 when the hoisting motor is deenergized.

A variable voltage system of control is provided for operating the hoisting motor M wherein its armature 8 is connected by means of conductors 14—15 in a closed circuit with the armature 16 of a generator G; the generator having a separately excited main field winding 17. The armature 16 of the generator is arranged to be driven at a constant speed by means of any suitable drive motor (not shown).

The direction and speed of the hoisting mo-

2

tor M are controlled by controlling the direction and value of the excitation current for the generator main field winding 17. The direction is controlled by a first up direction relay U and a first down direction relay D. The value of the excitation current will be controlled as hereinafter described. The operation of the up and the down direction relays is controlled by a second up direction relay UR and a second down direction relay DR which, in turn, are controlled by a manually operated control switch 18 mounted in the car in position to be controlled by the car attendant when he desires to effect the starting or stopping of the car. A car-running relay 19 is provided for conditioning the control system for operation when the car is to be moved and also for effecting the release of the brake 12 when the car is in operation. Directional relays U and D are controlled by means of the contacts 20 URI and DRI respectively of the directional relays UR and DR. In turn the contacts U1—U2 or D1—D2 of the relays U or D operate to control the circuit of the generator shunt field 17.

Any suitable system may be utilized for automatically decelerating the car and stopping it level with a floor in response to a stopping operation of the control switch 18. In the present case we have illustrated a pair of high speed levelling control relays UL and DL, and a stopping control relay LR. These relays are operated by a suitable levelling system (not shown) but indicated by contacts 21—22—23. A relay HS is provided to control the high speed movement of the car as will be explained in detail hereinafter; said relay being energized by closing of contact UR2 or DR2.

Whereas, many arrangements have been previously devised for the purpose of controlling elevator drive motors so as to obtain suitable acceleration-deceleration characteristics, the devices of the prior art have been deficient in certain respects. For example, certain prior systems have employed mechanical timing devices and thereby obtain pronounced step by step speed changes. In order to overcome these difficulties, the present invention provides a novel regulating means for stepless controlling of the energization of the field of the generator supplying current to the driving motor, so that improved accelerating and decelerating characteristics may be obtained throughout all starting and stopping operations of the car.

Our control system contemplates controlling the main field 17 by the use of a pair of gaseous 55 electronic discharge tubes 25 and 26. The tube

25 is provided with an anode 27, a grid 28, and a cathode 29. The tube 26 is provided with an anode 30, and a cathode 31. The cathodes may be of the heated type and supplied with current from the secondary winding 37 of the transformer 33 having a primary winding 34 connected to a suitable supply of alternating current represented by supply conductors 35 and 36, and additional secondary windings 32 and 38. The anodes of the tubes are connected to the secondary winding 32.

It will be obvious that the current supplied by the tubes 25 and 26 to the main field winding 17 will control the energization of that field winding and thereby control the output of the generator G. The output of the tube is controlled by providing a means for controlling the energization of the grid 28 of the tube 25. The means for controlling the grid comprises a phase shift network together with a suitable variable DC bias obtained from a cathode resistor; the operation of which is hereinafter more fully described.

The phase shift network comprises a secondary winding 38 of transformer 33 with a center tap 39; a condenser 40, and a resistor 41. The variable DC bias is obtained by suitably controlling the plate current through a triode tube 42 having anode 43, grid 44, and a cathode 45 heated by a suitable filament (not shown). This plate current passes through the cathode resistor 46 which is in the cathode circuit of the tube 42.

A suitable source of direct current is provided through conductors 47-48 which furnishes the plate current for tube 42 and controls the charging of a timing condenser 49 through resistors 50-51-52, as will be described hereinafter.

The starting of elevator car 2 is controlled by movement by the operator of control switch 18. When switch 18 is moved for the direction desired, such as Up, relay UR closes which in turn closes contacts UR1, UR2, and opens UR3. Assuming that the doors and gates have been closed, UR1 contact will cause relay U to close. This closes U1 and U2 so as to connect the generator field supply to the generator field for required polarity for travel in Up direction; when contact U3 closes, it in turn energizes MLB and HS relays. The opening of UR3 contact on UR relay disconnects the leveling system from the control system and allows the car to travel without interference from the leveling control system. This not only allows the car to leave the landing at which it has been parked, but will also allow the attendant to by-pass a landing, if desired.

When MLB relay closes, the generator field winding 17 is disconnected from the loop circuit conductor 14 by opening of MLB3 contact. The generator field winding 17 is differentially connected directly across the loop circuit when the car is not in motion, for the purpose of preventing residual voltage build up to prevent car movement until called for by the operator. Also, upon closing of relay MLB contact MLB2 closes thereby energizing solenoid 13 and releasing the brake 12. At the same time the contact MLB1 is closed, completing the circuit to generator field 17 from the rectifier output through conductors 53 and 54. This closing of HS relay causes contact HS1 to close and contact HS2 to open. This starts the elevator car 2 which accelerates under control of the grid rectifier tube 25 and the timing condenser 49.

When the attendant desires to stop at a land-

ing, the control switch handle is returned to neutral and the car slows down to a predetermined speed and continues to the landing where it will be automatically stopped by the leveling units 19 or 20 depending upon the direction of travel. The release of the control switch allows relay UR to drop out, which opens contacts UR1 and UR2, and closes contact UR3. The opening of UR1 does not deenergize relay U as it is held in by its own contact U2. The opening of contact UR2 causes relay HS to drop out, causing the car to slow down to leveling speed by opening of contact HS1 and closing of contact HS2. Opening of contact HS1 removes the charging current from the condenser 49, causing the elevator car 2 to start to slow down. The closing of HS2 applies a lower fixed value voltage to the control grid 44 from the resistor network 52, and establishes a fixed value of output voltage from the grid control rectifier tube 25. The value of this voltage is determined by the setting of the slide contact 55 on resistor 52. The setting of slide contact 55 is such as to provide for a low car speed suitable for movement of the car in the leveling zone prior to stopping. Thus, when HS1 opens and HS2 closes, the output voltage on conductors 53 and 54 decreases smoothly at a rate predetermined by the setting of the slide contacts 51 and 58 until it reaches a fixed predetermined value as established by setting of the slide contact 55.

The car then continues to travel at leveling speed toward the landing. When it reaches the leveling zone, contact 19 closes for Up travel. This closes relay UL, causing contact UL1 to close and this completes the circuit to relay U, bypassing contacts UR1 and U2. The car continues towards the landing until the leveling unit 21 reaches its zone thereby causing relay LR to close which opens contact LR1. The opening of LR1 opens the circuit through U2 and transfers control of relay U to leveling contact UL1. This makes it possible for the leveling unit 19 to stop the car when its contact opens and relay UL drops out and contact UL1 opens, thus causing relay U to drop out and disconnect conductors 53 and 54 of the rectifier output from the generator field 17. The opening of relay U also deenergizes relay MLB which opens contact MLB2 to open the circuit to brake solenoid 13, thereby permitting the springs to set the brake 12. Contact MLB3 simultaneously closes to connect the loop circuit. At the same time contact MLB4 opens to remove signal voltage from the grid 44 of tube 25, and contact MLB1 also opens.

The excitation of generator field 17 is provided by a half wave gaseous grid controlled rectifier tube 25 and a back wave gaseous rectifier tube 26 of the half wave type. Since tube 25 is a half wave rectifier, it will pass current in only one direction when its grid 28 has a potential on it that will allow the tube to conduct current between its anode 27 and cathode 29. Tube 25 will conduct on the positive half of each cycle of voltage supplied by the transformer secondary winding 32. Therefore, generator field 17 receives half wave pulses from tube 25, and since the generator field is highly inductive, it attempts to discharge during the negative half of each cycle. Tube 26 provides a low resistance path for this discharge allowing current to flow through it from anode 30 to cathode 31. This discharge current is in the same direction as the current provided by tube 25 and combines therewith to result in a continuous flow of current of low

ripple characteristics through the generator field 17. By controlling the amount of current passed through tube 25 it is possible to control the amount of excitation of the generator field winding 17 and thus the output of the generator which in turn controls the speed of the motor M and the elevator car.

When no conduction through the tube 25 is desired, as when the car is not moving, a negative bias is applied to grid 28 of sufficient value to render the tube non-conductive. This bias is established by tap 56 on resistor 52, and is set so as to make the cathode 29 positive of sufficient value with respect to the grid 28, thereby biasing the tube 25 to "cut-off" condition. With tap 56 set so that tube 25 will not conduct, the closing of contact HSI provides a positive voltage on grid 44 of tube 42 through the resistor 46. This is by-passed by condenser 49. The charging of condenser 49 takes place through the resistor 50, and this charging current causes a voltage drop through resistor 50, which slowly builds up to its maximum value until the condenser 49 is fully charged. Thus, the control grid 44 of tube 42 is slowly made more positive as condenser 49 becomes charged. As the grid 44 controls the amount of current passed through tube 42, the voltage drop through the resistor 46 also changes, reaching a maximum value when condenser 49 is fully charged. The voltage drop across resistor 46 is combined differentially with voltage drop on resistor 52 between conductor 47 and tap 56. The increase in voltage across resistor 46 slowly changes grid 28 to a more positive value allowing grid control tube 25 to conduct more and more of each positive half of each cycle.

Since complete control for full conduction of the positive cycle through tube 25 cannot be obtained by the change of D. C. bias on grid 28, an A. C. voltage of suitable value produced by the phase shift network is combined with the D. C. bias. This is obtained from secondary winding 38 of transformer 33. Voltage from this winding is shifted out of phase with that of winding 32 by means of resistor 41 and condenser 49 as is well known in the art. The output of the phase shift circuit is combined with the D. C. bias and serves to control the grid 28 so as to provide control over the full working portion of the positive cycle of tube 25.

The rate of charge of condenser 49 which controls acceleration of the car 2 is controlled by the position of tap 57 on the resistor 50. Likewise, the deceleration rate is set by means of tap 58 on resistor 51. The top speed of the car is adjustably controlled by setting of tap 59 on resistor 52. Thus, rates of acceleration and deceleration, maximum top speed, and leveling speed can be readily adjusted to meet various field conditions.

Thus, it will be appreciated that by reason of the arrangement of the invention, commercially available standard type compound generators may be employed in conjunction with our novel electronic generator field control system to obtain an improved type stepless acceleration-deceleration performance. Hence, improved operation is obtained without resort to use of expensive and complicated special generator field windings or special control apparatus designed to suit various type generators as produced by present day manufacturers. A particular feature and advantage of the invention is that it greatly facilitates initial installation adjustment of the generator control equipment because pre-

liminary adjustment for maximum car speed; levelling speed; acceleration and deceleration can be made before the motor-generator set is started up and without requiring movement of the car to check the adjustments. Thus, much of the expense and difficulties and hazards incidental to prior methods of adjustment are eliminated. Also, the system lends itself readily to easy modification of the speed and acceleration performance characteristics of the controlled elevator.

It will of course be understood that whereas the invention has been shown and described in detail only in conjunction with a simplified elevator control system, it is equally applicable to use in other more complex systems and in combination with any other control devices as may be required to suit different installations.

What is claimed is:

1. A variable speed elevator motive power system comprising a motor having its field winding supplied from a source of electrical energy and a generator connected to supply armature current to said motor, a field winding for said generator, an alternating potential supply, means including a grid-controlled rectifier for connecting said supply to said generator field winding, an insulating control tube having at least a cathode and a control grid and an anode, an input timing circuit comprising a capacitance and a resistance connected to said control grid, and connections for applying an output voltage furnished by said control tube to the grid of said grid-controlled rectifier.

2. The invention in accordance with claim 1, and a phase-shifting circuit energized from said alternating potential supply, said phase-shifting circuit being connected in series with the potential furnished by said control tube thereby to extend the region of control of said rectifier to values beyond that established by the direct current bias derived from said control tube.

3. The invention in accordance with claim 1, and means for adjusting the value of said bias potential.

4. The invention in accordance with claim 1, and means for adjusting the value of said bias potential, and means for selectively controlling the rate of increase of potential furnished by said control tube.

5. The invention in accordance with claim 1, and means for adjusting the value of said bias potential, and means for selectively controlling the rate of decrease of potential furnished by said control tube.

6. The invention in accordance with claim 1, a manually controlled resistor, and means responsive to the condition of said controlled resistor for adjusting the magnitude of said bias potential.

7. The invention in accordance with claim 1, a manually controlled resistor, and means responsive to the condition of said controlled resistor for adjusting the magnitude of said bias potential, and means for selectively controlling the rate of increase of potential furnished by said control tube.

8. The invention in accordance with claim 1, a manually controlled resistor, and means responsive to the condition of said controlled resistor for adjusting the magnitude of said bias potential, and means for selectively controlling the rate of decrease of potential furnished by said control tube.

9. The invention in accordance with claim 1,

and means for applying a charging potential to said capacitance to establish a predetermined maximum value of potential applied to the grid of said rectifier.

10. The invention in accordance with claim 1, and means for applying a charging potential to said capacitance to establish a predetermined maximum value of potential applied to the grid of said rectifier, and means for selectively controlling the rate of increase of potential furnished by said control tube.

11. The invention in accordance with claim 1, and means for applying a charging potential to said capacitance to establish a predetermined maximum value of potential applied to the grid of said rectifier, and means for selectively controlling the rate of decrease of potential furnished by said control tube.

12. The invention in accordance with claim 1, and means for applying a charging potential to said capacitance to establish a predetermined lower operating value of potential applied to the grid of said rectifier.

13. The invention in accordance with claim 1, and means for applying a controlled direct current bias potential between the anode and the grid of said control tube, to control the value of potential furnished by said control tube, and means for providing a smooth transition from the maximum value of voltage furnished by the control tube to a predetermined value to provide the desired leveling speed of the elevator car.

14. The invention in accordance with claim 1, and means for biasing said rectifier to cut-off.

15. A variable speed elevator motive power system comprising a motor having its field winding supplied from a source of electrical energy and a generator connected to supply armature current to said motor, a field winding for said generator, and alternating potential supply, means including a grid-controlled rectifier for connecting said supply to said generator field winding, an insulating control tube having at least a cathode and a control grid and an anode, an input timing circuit comprising a capacitance and a resistance connected to said control grid, connections for applying an output voltage furnished by said control tube to the grid of said grid-controlled rectifier, and means for applying a controlled direct current bias potential between the anode and the grid of said control tube, to control the value of potential furnished by said control tube.

16. A variable speed elevator motive power system comprising a motor having its field winding supplied from a source of electrical energy and a generator connected to supply armature current to said motor, a field winding for said generator, an alternating potential supply, means including a grid-controlled rectifier for connecting said supply to said generator field winding, an insulating control tube having at least a cathode and a control grid and an anode, an input timing circuit comprising a capacitance and a resistance connected to said control grid, connections for applying an output voltage furnished by said control tube to the grid of said grid-controlled rectifier, and means for applying a controlled direct current bias potential between the anode and the grid of said control tube, to control the value of potential furnished by said control tube, and means for selectively controlling the rate of increase of potential furnished by said control tube.

17. A variable speed elevator motive power system comprising a motor having its field winding supplied from a source of electrical energy and a generator connected to supply armature current to said motor, a field winding for said generator, an alternating potential supply, means including a grid-controlled rectifier for connecting said supply to said generator field winding, an insulating control tube having at least a cathode and a control grid and an anode, an input timing circuit comprising a capacitance and a resistance connected to said control grid, connections for applying an output voltage furnished by said control tube to the grid of said grid-controlled rectifier, and means for applying a controlled direct current bias potential between the anode and the grid of said control tube, to control the value of potential furnished by said control tube, and means for selectively controlling the rate of decrease of potential furnished by said control tube.

18. A variable speed elevator motive power system comprising a motor having its field winding supplied from a source of electrical energy and a generator connected to supply armature current to said motor, a field winding for said generator, an alternating potential supply, means including a grid-controlled rectifier for connecting said supply to said generator field winding, an insulating control tube having at least a cathode and a control grid and an anode, an input timing circuit comprising a capacitance and a resistance connected to said control grid, connections for applying an output voltage furnished by said control tube to the grid of said grid-controlled rectifier, and a rectifier tube connected across said generator field winding and having its cathode connected to that side of said winding connected to the cathode of said grid-controlled rectifier, to provide a low resistance path for the discharge of energy stored in said generator field winding by conduction through said grid-controlled rectifier.

19. A variable speed elevator motive power system comprising a motor having its field winding supplied from a source of electrical energy and a generator connected to supply armature current to said motor, a field winding for said generator, an alternating potential supply, means including a grid-controlled rectifier for connecting said supply to said generator field winding, an insulating control tube having at least a cathode and a control grid and an anode, an input timing circuit comprising a capacitance and a resistance connected to said control grid, connections for applying an output voltage furnished by said control tube to the grid of said grid-controlled rectifier, and a rectifier tube connected across said generator field winding to provide a low resistance path for the discharge of energy stored in said generator field winding by conduction through said grid-controlled rectifier.

20. A variable speed elevator motive power system comprising a motor having its field winding supplied from a source of electrical energy and a generator connected to supply armature current to said motor, a field winding for said generator, an alternating potential supply, means including a grid-controlled rectifier for connecting said supply to said generator field winding, an insulating control tube having at least a cathode and a control grid and an anode, an input timing circuit comprising a capacitance and a resistance connected to said control grid, connections for applying an output voltage furnished by said con-

trol tube to the grid of said grid-controlled rectifier, and means for applying a controlled direct current bias potential between the anode and the grid of said control tube, to control the value of potential furnished by said control tube, and means for providing a smooth transition from the maximum value of voltage furnished by the control tube to a selectable lesser value.
